UNITED STATES PATENT OFFICE

165,491

HOBBYHORSE

Robert M. Spangler, Chicago, Ill.

Application September 7, 1950, Serial No. 12,099

Term of patent 14 years

(Cl. D34—15)

To all whom it may concern:

Be it known that I, Robert M. Spangler, a citizen of the United States of America, residing at Chicago, in the county of Cook and State of Illinois, have invented a new, original, and ornamental Design for Hobbyhorse, of which the following is a specification, reference being had to the accompanying drawing, forming part thereof.

Fig. 1 is a front perspective view of a hobbyhorse, showing my new design; and

Fig. 2 is a rear perspective view thereof.

I claim:

The ornamental design for a hobbyhorse, as shown.

ROBERT M. SPANGLER.
